WILLIAM F. HOLSKE AND B. T. BABBITT, OF NEW YORK, N. Y.

Letters Patent No. 91,018, dated June 8, 1869.

IMPROVEMENT IN VELOCIPEDES.

The Schedule referred to in these Letters Patent and making part of the same.

To all whom it may concern:

Be it known that we, WILLIAM F. HOLSKE and B. T. BABBITT, of New York city, in the county and State of New York, have invented a new and useful Improvement in Velocipedes; and we do hereby declare that the following is a full, clear, and exact description thereof, which will enable others skilled in the art to make and use the same, reference being had to the accompanying drawings, forming a part of this specification, in which—

Figure 1 represents a side elevation, partly in section, of our improved velocipede.

Figure 2 is a plan or top view, partly in section, of the same.

Figures 3 and 4 are detail side views, on an enlarged scale, of the driving-mechanism.

Similar letters of reference indicate corresponding parts.

The main object of this invention is to produce a novel mechanism for propelling velocipedes and other vehicles by means of muscular or other power, said power being applied by persons, animals, or machines placed upon and conveyed by the said vehicles.

The invention consists in the application of friction-clutches to the edges of wheels to be revolved, said clutches being preferably made in form of friction-rollers, operated by suitable mechanism.

The invention consists, also, in so arranging the aforesaid friction-clutches, in pairs or oscillating frames, that they can be readily thrown in or out of gear, to propel the machine in either direction.

A, in the drawing, represents the driving-axle of our improved velocipede.

It has its bearings in a frame, B, of suitable form and construction, and may be in front or rear of the frame, as may be desired.

In the drawing, it is represented in rear, the front end of the frame being supported by the steering-wheel C, hung in a swivel-post, D, as shown.

The steering-post can, by means of suitable mechanism, be operated.

The drawing represents a jointed rod, E, which is, by means of bevel-gear wheels a a, connected with the steering-post.

The driving-axle A is hung in or supported by two wheels, F F.

On the axle are mounted two disks, b b, at suitable distances apart.

To the edges of these disks, by means of friction-clutches or pawls, the requisite power is applied.

The friction-pawls we prefer to make in form of small rollers, c c, which are, with their projecting axle-ends, fitted through slots, d d', of plates G.

These plates G are suspended from the axle A, one on each side of each disk b; and the two, on the sides of each disk, are connected with each other by pins or bolts, e e.

There is one roller, c, in front, and one, c', in rear of each disk.

The slots f, in the middle portions of the plates G, are of inverted U-shaped form, or they may be said to be square, with lips, g, suspended from above, as shown.

When the plates are so suspended that the lips g are in front of the axle, as in figs. 1 and 3, the rear roller will, with its edge, be in contact with the disk b. When, however, the lip g is in rear of the axle, as in fig. 4, the front roller, c, will be in gear, as shown.

The slots d d' are not concentric to the axle, but are somewhat nearer, at their lower ends, to the axle, so that the roller in gear is wedged in between its bearing and the edge of the disk b.

When, therefore, the plates G are so swung on the axle as to carry the roller which is in contact with the disk upward, the roller will be forced against the disk, and will, by its friction, propel the same.

Thus, in fig. 3, the axle will be revolved in the direction of the arrow 1, when the plates G are swung in the same direction, while, in the position shown in fig. 4, the axle can only be turned in the direction of the arrow 2.

Levers H H are connected with the plates G, so that the latter may readily be adjusted on the axle in the position of figs. 3 or 4, as it may be desired to move backward or forward.

The plates G are, by means of rods h h, connected with the ends of a cross-bar, i, of a vertical arbor, j, said arbor having its bearings in the frame, as shown.

A cross-head, k, is formed on the upper end of the arbor j, and has pivoted foot-supports, l l, at its ends.

The rider has the feet in the supports l, and, as he moves them alternately backward and forward, to oscillate the arbor j, he will oscillate the plates G in opposite directions, causing the clutch-roller of one to act while the other is drawn back for the next stroke. Continuous action is thus imparted to the axle A.

This device is peculiarly adaptable to ladies' use, as the action required for propelling the vehicle is easy and simple.

A steam or atmospheric engine may also be placed upon the frame, to propel the device.

We do not confine ourselves to the particular mode of arranging the friction-clutches as above described, but consider it as our invention to apply them in any other suitable form to the edge of a disk or wheel on a velocipede or other vehicle.

Having thus described our invention,

What we claim as new, and desire to secure by Letters Patent, is—

1. The application of reversible friction-clutches, working against the edges of disks or wheels, as de-

scribed, to propel a velocipede, or other vehicle, as specified.

2. The pivoted plates G, carrying the friction-rollers c c', in eccentric slots, as described, and so arranged as to be adjustable on the driving-axle, to reverse the motion, as specified.

3. The levers H H, when arranged, to adjust the plates G, on the axle A, substantially as herein shown

and described, for the purpose of reversing the motion of the vehicle, as specified.

WM. F. HOLSKE.
B. T. BABBITT.
